UNITED STATES PATENT OFFICE.

JULIUS C. TOURNIER, OF SCHENECTADY, NEW YORK, ASSIGNOR TO GENERAL ELECTRIC COMPANY, A CORPORATION OF NEW YORK.

ELECTRIC CUT-OUT.

SPECIFICATION forming part of Letters Patent No. 768,351, dated August 23, 1904.

Application filed January 21, 1901. Serial No. 43,986. (No model.)

To all whom it may concern:

Be it known that I, JULIUS C. TOURNIER, a citizen of the United States, residing at Schenectady, county of Schenectady, State of New York, have invented certain new and useful Improvements in Electric Cut-Outs, of which the following is a specification.

This invention relates to that class of mechanical cut-outs known as "two-button snap-s 10 switches," adapted to be set in flush with a wall or switchboard. In these switches the movable contact is actuated in one direction by one push-button and in the opposite direction by a second push-button, having a "snap" 15 action imparted to it in each direction of movement by a spring.

The object of my invention is to improve and simplify some details of construction in order to facilitate the making of the switch, 20 increase its durability, and render it easy to connect up, inspect, and repair.

In the accompanying drawings, Figure 1 is a longitudinal sectional elevation of a switch embodying my improvements, the switch being closed. Fig. 2 is a cross-sectional elevation of the same. Fig. 3 is a longitudinal section showing the switch open. Fig. 4 is a plan view with the face-plate removed. Fig. 5 is a top plan of the face-plate. Fig. 6 is a plan 30 view of the supporting-bar with the holes for the attaching-screws omitted. Fig. 7 is an axial section of the rocker and switch arms and hubs. Fig. 8 is a perspective view of one of the switch-arm hubs, and Fig. 9 is a plan view of a switch-arm.

The casing A is of insulating material, preferably porcelain, molded to the proper shape—such, for example, as a rectangular box having an open top. In each corner of the box 40 is an upright standard B, consisting of a strip of metal having an angular foot b, receiving a screw C, by which it is secured to the bottom of the box. The upper end of each standard is bent inwardly to receive a binding-screw D for the line-terminals. An inwardly-projecting arm b' on each standard carries a stationary spring-contact E, consisting of two independent clips or of a strip of copper doubled into a U-shaped clip and riveted to said arm

at the point where it straddles it. The clips 50 at one end of the box have their open ends upward and those at the other end downward. A rib a runs down each end of the box between the standards, one or both of them being continued along the bottom of the box at a'. Lying lengthwise on top of the box is a flat supporting-bar F, whose ends project beyond the ends of the box and are received in shallow grooves a² in the upper edge of the box. Screws G are inserted through long countersinks a³ 60 in the ends of the box and pass into the bar to fasten it to the box.

To the under side of the supporting-bar is attached a transverse yoke H, having parallel legs h extending into the box. In the ends 65 of these legs is carried a transverse shaft I, on which is journaled a rocker K and two double-ended switch-arms or movable contacts L, one on each side of the rocker and each in line with the clips E on that side of 70 the box. Each switch-arm is carried on a hub M of insulation, having a polygonal portion m fitting an eye l at the middle of the switch-arm. An insulating washer M' lies between the switch-arm and the leg of the 75 yoke. The rocker carries a stud k, entering a hole in the hub M and so locking them all together.

Pivoted to each end of the rocker is a link N, preferably doubled, as shown, and having 80 a broad upper end, by which it is attached to a button or plug P, extending up through a suitable hole f in the supporting-bar F. When one of the buttons is pushed in, as shown in Fig. 1, the switch-arms enter and 85 connect their respective pairs of contact-clips. When the other button is pushed in, the rocker is rocked and the switch-arms are withdrawn from the clips, as shown in Fig. 3.

In order to give a quick snap action to the 90 switch, so that the switch-arms will be moved into and out of the clips with a sudden jerk, and thus lessen the danger of drawing an arc, the middle of the rocker has a beveled lug k', whose two edges are inclined in opposite directions at the same angle to the upper edge 95 of the rocker. A detent-plunger R, having at its lower end two inclined edges adapted to

coöperate with those of the lug h' , is mounted to reciprocate in transverse guides on the yoke. The lower guide is a bar h' , while the upper guide is preferably an offset portion h^2 of the yoke. A spring S lies between the upper guide and shoulders on the plunger and keeps it pressed yieldingly against the lug h' .

An ornamental face-plate T covers the top of the box and is secured to the supporting-bar F by screws t . The plate has countersunk holes through which the buttons P project.

By removing the face-plate the circuit connections can be easily made, the leading-in wires being led up through the holes a^4 in the corners of the wall of the box to the binding-screws at the tops of the standards. Moreover, when the face-plate is off all parts of

the switch can be readily inspected and tested, and the mechanism can be removed from the casing, if desired.

What I claim as new, and desire to secure by Letters Patent of the United States, is

In a cut-out, the combination with a yoke, of a rocker rotatably journaled therein and having a beveled lug, a bar extending across the yoke, a plunger passing through the bar and engaging with the lug, and a spring pressing on the plunger.

In witness whereof I have hereunto set my hand this 18th day of January, 1901.

JULIUS C. TOURNIER.
